CODE DATER

Robert F. McVicker, Anderson, Ind., assignor to Lynch Corporation, Anderson, Ind., a corporation of Indiana

Filed Sept. 28, 1959, Ser. No. 842,701

3 Claims. (Cl. 101—377)

This invention relates to a code dater particularly 15 adapted for dating cartons passing through a cartoning machine.

One object of the invention is to provide a code dater including a date stamp carrier which may be quickly 20 operated to remove date stamps and substitute others, thus reducing to a minimum the down time necessary to effect a change of code date, the construction being such as to utilize standard existing dater stamps instead of requiring special stamps.

Another object is to provide a date stamp carrier comprising a date stamp carrier and a date stamp retainer, the retainer being adjustable from a retaining position to any one of a number of date stamp-removal positions to permit individual removal of a date stamp and the 25 substitution of another, whereupon the retainer may be adjusted to its initial or retaining position.

Still another object is to provide detent means to normally hold the retainer in its retaining position yet permit ready movement thereof to non-retaining position without the aid of any tools.

A further object is to provide means in the form of 30 magnets to temporarily retain the date stamps in mounted position while the retainer is being adjusted to the various positions permitting removal of the individual date stamps and replacement thereof, such as—each morning before beginning the operation of the cartoning machine for the day. The magnets prevent the date stamps from falling out and very little pressure is needed to remove one while the magnets keep the others in alignment.

Still a further object is to provide a date stamp carrier having radial grooves to receive date stamps which date stamps have cross grooves, the date stamp retainer having an annular bead to fit into the cross grooves to retain the date stamps in their proper radial locations when the retainer is returned to retaining position.

With these and other objects in view, my invention consists in the construction, arrangement and combination of the various parts of my code dater, whereby the objects above contemplated are attained, as herein-after more fully set forth, pointed out in my claims and illustrated in detail on the accompanying drawing, wherein:

Fig. 1 shows an end elevation of a carton date stamping mechanism with my improved date stamp carrier and retainer associated with an opposed back-up segment, and illustrates the operation of the dater on a carton;

Fig. 2 is a side elevation of the mechanism of Fig. 1 and includes a vertical sectional view through the date stamp carrier taken on the line 2—2 of Fig. 1;

Fig. 3 is an enlargement of Fig. 2 showing the parts adjusted to a different position;

Fig. 4 is a face view of a date stamp carrier and date stamps therein as taken on the line 4—4 of Fig. 3;

Figs. 5 and 6 are sectional views on the lines 5—5 of Fig. 2 and 6—6 of Fig. 3, respectively, showing the

2

relative positions of the parts for the different adjustments depicted in Figs. 2 and 3 (Fig. 2 being a sectional view on the line 2—2 of Fig. 4); and

Figure 7 is a perspective view of one of the date stamps 5 removed from its mounted position in Fig. 4.

On the accompanying drawing I have used the reference numeral 10 to indicate a date stamp carrier which carrier is in the form of a thick disc secured to a shaft 12 which rotates one each carton fed through the cartoning machine. A pin 13 as shown in Fig. 3 may be used for this purpose. Referring to Fig. 1, a back-up segment 14 cooperates with the date stamp carrier to date a carton C, the segment 14 having a hard rubber face 16 to absorb the shock of multiple cartons passing through the machine and prevent excessive wear on the date stamps. The face 16 also evens out the difference in height of the stamps and gives a uniform dating imprint on the carton C.

I provide a date stamp retainer 18 in the form of a hub having a disc-like flange 28 in which flange a slot 32 is provided for a purpose which will hereinafter appear. The carrier 10 has date stamp receiving slots 20 therein (six slots are shown in Fig. 4) to receive the date stamps S¹ to S⁶ inclusive. The date stamps as shown in Fig. 7 are square, elongated dies to be received in the slots 20 and each is provided with a notch 26.

The date stamps are advantageously held in the slots 20 by magnets 22 pressed into bores 24 of the carrier 10, and are adapted to be retained in the desired position for operation by an annular bead 30 on the flange 28 of the date stamp retainer 18 as shown in Fig. 2. The carrier 10 has a groove 31 to receive the bead 30.

The shaft 12 is provided with a detent 34 in which 35 a detent ball 36 is normally seated as shown in Figs. 2 and 5 by a detent spring 38. A plug 40 in the retainer 18 backs up the spring 38. A collar 42 held in position on the shaft 12 by a set screw 44 permits rotation of the date stamp retainer 18 but prevents axial movement thereof with respect to the shaft 12.

Referring to Fig. 1, the cartoning machine has a carton feeding segment 46 on a shaft 47 and a pair of back-up rollers 48 for properly feeding the carton C to position between the date stamp carrier 10 and the 45 back-up segment 14. The carrier 10, the back-up segment 14 and the carton feeding segment 46 are suitably geared together by means of the gears 50, 52, 54, 56 and 57 which are supported in an obvious manner for rotation with respect to the frame 58 of the cartoning machine.

Practical operation

In the operation of my code dater, the parts are normally in the position of Figs. 1, 2 and 5 when ready for 55 operation of the cartoning machine. When it is desirable to change one or more of the date stamps S¹, S², etc., the date stamp retainer 18 is rotated from the retaining position of Figs. 2 and 5 with the ball 36 in the detent 34, to a position with the slot 32 opposite the desired date stamp to be replaced, for instance, S⁴ as in Figs. 3 60 and 6 whereupon the date stamp S⁴ may be removed in a direction away from the magnet 22 through the slot 32 and another one substituted. The magnet 22 holds the substituted date stamp temporarily in position and the retainer 18 is then rotated back to the original position of Figs. 2 and 5, thus retaining the date stamp S⁴ as well as all the others in position.

As shown in Fig. 5, the slot 32 is normally (when the ball 36 is in the detent 34) in a position out of alignment with any of the date stamps, being just to the 65 left of the last one (S¹). Thus, the flange 28 and the bead 30 hold the date stamps in their slots 20 and locate them radially respectively.

From the foregoing description it will be obvious that I have provided a code dater that is readily operable to change date stamps, thus providing a simple and efficient code dater for use in connection with wrapping machines, cartoning machines, and the like, the construction being such as to reduce date-change time to a minimum.

Some changes may be made in the construction and arrangement of the parts of my code dater without departing from the real spirit and purpose of my invention, and it is my intention to cover by my claims any modified forms of structure or use of mechanical equivalents which may reasonably be included within their scope.

I claim as my invention:

1. In a code dater of the character disclosed, a disc-like date stamp carrier having open, radial date stamp receiving slots in one face thereof to locate date stamps circumferentially, magnetic means for temporarily holding date stamps in said slots against the bottoms thereof, date stamps for said slots having notches in the sides thereof opposite the bottoms of said slots, a date stamp retainer having a flange overlying the date stamps and an annular bead to enter said notches and thereby locate the date stamps radially, and means for normally retaining said retainer in retaining position, said retainer having a notch in the flange thereof movable to a position over any one of the date stamps, said last notch interrupting said bead which cooperates with said last notch for permitting removal of said any one of the date stamps from its slot in the carrier and replacement by another date stamp.

2. In a code dater, a shaft, a disc-like date stamp carrier thereon having radially extending recesses open at one face of said carrier to receive date stamps, a magnet associated with each recess to temporarily retain a date stamp seated therein, date stamps for said recesses having crosswise notches therein, and a date stamp retainer comprising a disc-like member adjacent said carrier and retaining the date stamps in said recesses,

40

said retainer being rotatable relative to said shaft, detent means for normally holding the same in one position of rotation relative thereto, said retainer having a slot out of alignment with any of said date stamps when said detent means is operable and rotatably movable to alignment with any thereof for permitting removal of the same and replacement thereof, said retainer having an annular bead to engage in all of the crosswise notches of said date stamps when said detent means is operable, said annular bead being interrupted by said slot to cooperate therewith in permitting removal and replacement of date stamps relative to said recesses.

3. In a code dater, a shaft, a disc-like date stamp carrier thereon having radially extending recesses in one face thereof to receive date stamps, date stamps for said recesses having crosswise notches opposite the bottoms of said recesses, a date stamp retainer comprising a disc-like member adjacent said one face of said carrier for retaining the date stamps in said recesses, said retainer being rotatable relative to said shaft, means for normally holding the same in one position of rotation relative thereto, said retainer having a slot out of alignment with any of said date stamps when said means is operable and rotatably movable to alignment with any thereof for permitting removal of the same through said slot and replacement thereof in said recess, and said retainer having circumferentially extending means engaging in said crosswise notches to positively retain said date stamps in said recesses and in circumferential alignment, said last means being circumferentially interrupted by said slot.
